Arthur B. Jenkins,
ATTORNEY.

UNITED STATES PATENT OFFICE.

CHARLES A. BAILEY, OF CROMWELL, CONNECTICUT.

TOY PISTOL.

1,387,095.

Specification of Letters Patent.

Patented Aug. 9, 1921.

Application filed May 28, 1919. Serial No. 300,419.

To all whom it may concern:

Be it known that I, CHARLES A. BAILEY, a citizen of the United States, residing in Cromwell, in the county of Middlesex and 5 State of Connecticut, have invented a new and Improved Toy Pistol, of which the following is a specification.

My invention relates to that class of toys used for exploding so-called "paper caps," 10 and an object of my invention, among others, is to provide a device of this class having special means for feeding a strip or tape having caps disposed at intervals therealong.

One form of device embodying my invention, and in the construction and use of which the objects herein set out, as well as others, may be attained, is illustrated in 15 the accompanying drawings, in which—

Figure 1 is a view in side elevation of a toy pistol embodying my invention.

Fig. 2 is a top view of the same.

My improved toy pistol, as illustrated in the drawings herein, embodies a frame comprising a receiver 5 having a barrel portion 6 projecting forwardly therefrom and a handle 7 extending downwardly from its rear end. A special feature of my invention includes a cap feeding anvil wheel so 25 constructed that in its operation it will feed a tape having caps disposed at intervals along its length into position to be struck by a hammer acting against the wheel to explode the caps. In the structure herein 30 shown this cap feeding anvil wheel 8 has several faces 9, six faces being shown, against which a hammer 10 strikes under the force of a spring 11. A feeding guide 12 is located to coöperate with the wheel in its 35 feeding action, the paper tape 13 extending between the wheel and the guide and being fed along by contact of the wheel with the guide.

In the preferred form of construction, 40 and as shown herein, this guide is pressed with more or less force against the wheel. The guide itself may have spring qualities sufficient to press it against the wheel with the desired force, the ends of this spring 45 guide being secured as in clips 14. It is also preferred, although this is not absolutely essential, that this guide shall conform to a considerable extent to the shape of the wheel, and, as shown herein, the guide

is of angular shape to fit two adjacent faces 55 of the wheel. By such construction the tape is held snugly against the wheel and the sharp corners of the wheel act to bite into the tape and thereby feed it along. The spring pressure of the guide against 60 the tape also prevents fire from being communicated to unexploded caps on the tape.

The end of this guide may be provided with a short lip 15 bent outwardly and serving as a means for releasing the tape, as 65 for the purpose of adjusting its position on the guide. This lip also serves as a guard to prevent fire from flashing downwardly and burning the trigger finger of the operator, that acts against the trigger 16, which trigger, 70 in the structure herein illustrated, is an integral part of the hammer. The tape may be comprised in a roll 17 mounted on a roll support 18 projecting from the frame.

Any desired means for rotating the wheel 75 8 may be employed, a satisfactory construction comprising ratchet teeth 19 formed on the side of the wheel in position to be engaged by a feeding arm 20 extending from the hammer structure.

The operation will be readily understood 80 from the foregoing description from which it will be seen that each time the wheel is given a one-step movement two of its corners will be pressed into the substance of the 85 tape against the pressure of the guide 12, and the tape will thus be caused to move along the guide to position the caps thereon for impact of the hammer against the anvil wheel 8.

To provide for the bulges on the tape 90 caused by the caps and permit the guide 12 to rest snugly against the surface of the wheel I make depressions in the wheel or guide to receive said bulges, in the construction herein shown such depressions 21 being formed in the guide by bending the latter to form grooves extending laterally across the guide.

In accordance with the provisions of the 100 patent statutes, I have described the principles of operation of my invention, together with the device which I now consider to represent the best embodiment thereof; but I desire to have it understood that the device 105 shown is only illustrative, and that the invention may be carried out by other means.

I claim—

1. A toy pistol comprising a frame, a cap feeding wheel rotatably mounted on the frame and having an angularly shaped periphery, and a guide having an angular shape to correspond with the angles of said wheel, said guide being pressed into contact with said wheel to coöperate therewith in feeding a tape therealong.
10. 2. A toy pistol comprising a frame, a cap feeding wheel having angularly disposed

faces, a guide of angular shape to fit said wheel, and means for pressing the guide into contact with said wheel.

3. A toy pistol comprising a frame, a cap feeding anvil wheel rotatably mounted on the frame and having notches, and a member pivotally mounted on the frame and having a rigid projection to engage with said notches to rotate said wheel.

CHARLES A. BAILEY.
